UNITED STATES PATENT OFFICE

OSCAR WERNER, OF SOUTH BEND, INDIANA, ASSIGNOR TO WESTINGHOUSE ELECTRIC & MANUFACTURING COMPANY, A CORPORATION OF PENNSYLVANIA

AIRPORT FLOOD-LIGHTING PROJECTOR

Application filed June 22, 1927. Serial No. 200,565.

My invention relates to illuminating devices and more particularly to focusing means for such devices.

Incandescent lamps have proved very satisfactory as a source of illumination for certain types of illuminating devices. However, in order to secure the proper control of the projected beam, it has been found desirable that the focusing means provide three-dimensional adjustment of the lamp and also that the lamp be rotatably mounted to secure the proper filament position. It is desirable that focusing of the lamp be done from outside the projector housing, so that the reflector is not exposed unnecessarily to dust and moisture while focusing the lamp. The focusing device must be capable of fine adjustment, so that a sharp focus may be obtained. In addition, the device should be rugged and dependable.

Therefore, it is among the objects of my invention to provide a focusing device which shall have the above mentioned desirable features and which shall be simple, rugged and inexpensive to manufacture.

Referring to the accompanying drawings, in which like numerals of reference indicate like parts,

Figure 1 is a view partly in perspective and partly in section, of my focusing device as applied to a floodlight, and

Fig. 2 is a top plan view of the L-shaped adjusting member.

In order to better illustrate my invention, I have shown it in perspective in connection with a portion of a projector comprising a housing 6 in which a reflector 16, of the usual type, is mounted.

My focusing device comprises an L-shaped member 32 disposed in the housing in front of reflector 16 with one arm or branch, which I term the focusing branch 33, extending along the bottom of the housing at right angles to the reflector while the other branch, termed the lateral adjustment branch 34, is curved to conform to the curvature of the housing and extends at right angles to the first named branch.

Springs 37 and 38 are disposed midway along each branch between the L-shaped

member and the housing to bias the L-shaped member away from the housing. Bolts 41 and 42 engage the ends of the branches and project loosely through the housing. Thumb nuts 43 and 44, termed the focal and lateral 55 adjusting nuts, respectively, are disposed on the bolts and bear against the outside of the housing, so that movement of the nuts causes a corresponding movement of the ends of the respective branches.

The shank 46 of lamp standard 47 is threaded through the junction of the two branches 33 and 34 and is disposed in an upright position with regard to the L-shaped member.

A lamp socket 52 and incandescent lamp 53 are mounted on the shank 46, the shank being provided with cable terminal bushings (not shown) in which the cable terminals may be clamped by thumb screws 56. 70 The lamp is provided with downwardly extending prongs (not shown) which are engaged with the cable terminals by thumb screws 54.

The shank 46 of the lamp standard also 75 passes loosely through the housing 6 and is provided with a thumb nut 50, so that movement of the nut causes a corresponding up and down movement of the shank. This nut is termed a vertical adjustment nut. It 80 may be seen by inspection of the drawing that the L-shaped member will pivot about one or two of three pivotal points formed by shank 46 and nut 50, bolt 42 and nut 44, and bolt 41 and nut 43.

The shank 46 will turn in the L-shaped member so that the lamp 53 and lamp filament may be rotated to the most effective position. The shank may be locked with reference to the L-shaped member by means 85 of set screw 51.

In focusing the lamp, the first operation is to loosen or tighten all three thumb nuts until the lamp is at the desired elevation with respect to the reflector. The springs 37 and 38 cause the L-shaped member to move upwardly at either the ends or the junction when the corresponding thumb nuts are loosened. The second operation consists in loosening or tightening the thumb nut 44 100

(Fig. 1) until the lamp filament is at the desired lateral position. If the thumb nuts 43 and 50 are untouched, the lamp will remain at substantially a constant elevation during the lateral adjustment. When the desired lateral and elevational adjustments of the lamp have been completed, the thumb nut 43 in front of the socket is turned to the right or to the left in order to tilt the lamp forwardly or backwardly until the proper focal distance from the reflector is obtained. The focusing operation does not materially disturb the vertical or lateral adjustment.

As the projected area of the filament on the reflector varies for different positions of the lamp, the socket 52 and shank 46 are rotated until the desired projected area, and beam spread, is secured. The set screw 51 is then tightened to lock the lamp in the desired position.

My invention provides a quick and ready means for a three-dimensional adjustment of the lamp and means for rotating the lamp until the optimum position of the filament is obtained. The operation of focusing is readily accomplished from the outside of the lamp housing so that the interior of the projector is not unnecessarily exposed to dust. The adjustment is of the simple and rugged character and the unit is relatively inexpensive to construct.

Although I have described a specific embodiment of my device, I do not wish to be limited thereto. It is obvious that the lamp standard may be mounted at any part of the L-shaped member and three-dimensional adjustment secured. These and other modifications as may occur to those skilled in the art may be made without departing from the spirit and scope of my invention, as defined in the appended claims.

I claim as my invention:

1. In combination with a lamp housing, a focusing device comprising an adjusting member having three triangularly disposed pivotal points of adjustment, a lamp standard mounted at one pivotal point of said adjusting member and means for pivotally moving said adjusting member on any one or any two of said pivotal points and for regulating the elevation of said pivotal points with respect to said housing.

2. A focusing device comprising means for mounting said device on a lamp housing, an L-shaped member, a lamp standard mounted at right angles at the intersection of the branches of said L-shaped member, adjusting means at said intersection, and adjusting means at the ends of said L-shaped members whereby three-dimensional adjustment of the lamp standard is secured.

3. A focusing device comprising means for mounting said device on a lamp housing, an L-shaped member, a lamp standard rotatably mounted at right angles at the intersection

of the branches of said L-shaped member, adjusting means at the ends of said L-shaped members, and locking means for locking the standard with relation to said L-shaped member.

70

4. A focusing device for use in a lamp housing, including an adjustable plate having two pivotal points of adjustment and a lamp standard provided with a lamp socket and lamp, and projecting through the plate and housing at right angles thereto, and having screw threaded engagement with the plate, and a nut on the standard engaging the wall of the housing to constitute a third pivotal point of adjustment disposed in triangular relationship to the two first named pivotal points.

80

5. A focusing device for use in a lamp housing, including an L-shaped adjustable plate having adjusting means at the extremities of the branches of the plate and a lamp standard having a lamp socket and lamp mounted thereon mounted at the intersection of the branches of the L-shaped member and having screw threaded engagement with it and with a nut which engages the wall of the housing, whereby the lamp is adjustably and rotatably mounted with regard to the housing.

85

6. A focusing device comprising means for mounting said device on a lamp housing, an adjusting member having three triangularly disposed pivotal points of adjustment, a lamp standard rotatably mounted in and having screw threaded engagement with one portion of said adjusting member, said standard projecting through the housing, a nut on the standard outside of, and engaging, the housing to constitute one of the pivotal points of adjustment, and means for moving any portion of said adjusting member toward and away from said housing.

95

7. A focusing device comprising means for mounting said device on a lamp housing, an adjusting member having three triangularly disposed pivotal points of adjustment, a lamp standard rotatably mounted on and engaging one portion of said adjusting member, said standard projecting through the housing and adjusting means having screw threaded engagement between the standard and housing to constitute with the standard one of the pivotal points of adjustment.

100

In testimony whereof, I have hereunto subscribed my name this seventh day of June, 1927.

110

OSCAR WERNER.
